United States Patent Office

Des. 224,353

Patented July 18, 1972

224,353

TAPE PRINTER OR SIMILAR ARTICLE

Fred C. Rosenow, Northridge, Calif., assignor to Data Collection Systems, Inc., Northridge, Calif.

Filed Sept. 22, 1970, Ser. No. 25,134

Term of patent 14 years

Int. Cl. D18—99

U.S. Cl. D64—10

FIG. 1 is a perspective view of a tape printer or similar article embodying my new design;

FIG. 2 is a right side elevational view of the tape printer or similar article shown in FIG. 1;

FIG. 3 is a top plan view of the tape printer or similar article shown in FIG. 2;

FIG. 4 is a bottom plan view of the tape printer or similar article shown in FIG. 2;

FIG. 5 is a left end elevational view of the tape printer or similar article shown in FIG. 2; and

FIG. 6 is a right end elevational view of the tape printer or similar article shown in FIG. 2.

I claim:

The ornamental design for a tape printer or similar article, as shown.
